Inventor

Andrew J. Davis,

UNITED STATES PATENT OFFICE.

ANDREW J. DAVIS, OF HARTFORD, MICHIGAN.

SASH-HOLDER.

SPECIFICATION forming part of Letters Patent No. 361,864, dated April 26, 1887.

Application filed February 23, 1887. Serial No. 228,574. (No model.)

To all whom it may concern:

Be it known that I, ANDREW J. DAVIS, a citizen of the United States, residing at Hartford, in the county of Van Buren and State 5 of Michigan, have invented certain new and useful Improvements in Sash-Fasteners; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My present invention relates to improvements in that class of sash-fasteners wherein the sash may be held in a secure manner at any desired height in the frame, or locked to prevent ingress from the outside; and my improvements consist, essentially, of the novel 20 details of construction and general arrangement of parts, as will be hereinafter fully described, and pointed out in the claims.

In the accompanying drawings, Figure 1 25 represents a perspective view of my improved device; Fig. 2, a front elevation of the same; Fig. 3, a detail sectional view thereof applied to a sash, and Fig. 4 a detail sectional view of a modification.

30 Similar letters of reference indicate like parts in the several figures of the drawings.

In carrying out my invention I preferably provide a rectangular box, A, formed of cast-iron, and provided at its front opening with 35 a surrounding flange, B, having openings *a* for the reception of suitable screws to secure the said box within a corresponding recess in the edge of the window-sash, as shown.

Near the lower portion of the box or receptacle A is provided a roller, C, which is journaled upon the outer bent arm of a wire spring, D, the inner end of which is secured to the rear of the box in such manner as to allow the roller to project normally a slight 45 distance past the outer face of the surrounding flange B to impinge and revolve freely upon the frame of the window when the device is in operative relation therewith. To the rear of the roller C is provided a wedge-shaped slide, E, provided with a suitable handle, *e*, which projects through an elongated slot, *d*, in the side of the box A, for raising or lowering the said slide, to permit either the free revolution of the roller C or to project 50 it outwardly from the face of the inclosing-

box A and hold it in position to form a brake or stop to hold the sash at any desired point in the frame.

Near the upper end of the box A, and to one side of its interior, is provided a pin or stop, *f*, the object of which is such that when the slide is pushed down behind the roller C to force the same outwardly the upper end of the said slide can be pushed back under said pin or stop to hold the slide in position to 65 keep the roller thrown outwardly in contact with the window-frame to hold the sash at any point. In place, however, of using the box or receptacle A, the spring-actuated roller C and wedge-shaped slide E may be adjusted within 70 a recess formed in the edge of the sash, as shown in the drawings.

In the operation of my invention the device is adjusted in the recess in the edge of the sash with the handle *e* of the slide E projecting out of a slot in the front edge of the sash, as shown, it being only necessary, when the parts are thus arranged, to raise the sash to any desired point and push the slide E down behind the roller C by means of the 75 handle *e* to hold the sash securely in place, the roller projecting outwardly from the recess in the edge of the sash and impinging against the frame of the window to accomplish the desired result. To allow of the free 80 movement up or down of the sash, the slide E is raised from its engagement with the roller C, allowing the same to spring back into the recess the proper distance to insure the free 85 revolution of the said roller.

Having thus described my invention, I claim 90 as new and useful—

1. A sash-fastener consisting of a spring-actuated roller capable of being thrown in or out of contact with the frame of a window 95 through the medium of a wedge-shaped slide, substantially as and for the purpose specified.

2. A sash-fastener composed of a box or receptacle provided upon the interior thereof with a spring-roller, and a wedge-shaped slide 100 having a handle, and a pin or stop to hold the said slide in a locked position, substantially as described, and for the purpose specified.

In testimony whereof I affix my signature in presence of two witnesses.

ANDREW J. DAVIS.
